E. SEYFA RTH

METHOD AND MEANS OF MERCHANDISING PIECE GOODS

Filed Dec. 31. 1921

Inventor:
Edward Sayforth
By: J. J. Wilson
Attest.

UNITED STATES PATENT OFFICE.

EDWARD SEYFARTH, OF DIXON, ILLINOIS.

METHOD AND MEANS OF MERCHANTISING PIECE GOODS.

Application filed December 31, 1921. Serial No. 526,434.

To all whom it may concern:

Be it known that I, EDWARD SEYFARTH, a citizen of the United States, residing at Dixon, in the county of Lee and State of Illinois, have invented certain new and useful Improvements in Methods and Means of Merchandising Piece Goods, of which the following is a specification.

In the retail merchandising of piece goods it is customary for the prospective purchasers to take for inspection, samples of various grades and qualities of goods in which they are interested. Under the present practice, these samples are generally cut one at a time from the loose end of the piece goods, consequently causing considerable waste. Furthermore, much inconvenience and confusion is caused by the lack of means for properly identifying samples, and especially so by reason of the close similarity of shades, textures and designs. The primary object, therefore, of the present invention is to provide a novel method and means of merchandising piece goods with a view to overcoming the above and other objections. My invention aims by this method to provide a more convenient, practical and efficient way of merchandising piece goods with the view to benefiting both the seller and the buyer.

Another important object is the provision of novel means employed in connection with the merchandising of piece goods for furnishing certain desirable information and data in connection with each bolt of goods, which data shall be readily accessible, although normally concealed.

Still another important object is the provision of novel means for supporting a label or tab in a display position in connection with a bolt of goods; and furthermore, to support such label in co-operative relation with a sample holder containing samples of piece goods.

I have also aimed to provide means constructed in a simple and novel manner for the practice of said method of merchandising, and which may be produced at a comparatively low cost and will be serviceable and practical for the purposes intended.

Other objects and attendant advantages will be appreciated by those familiar with this art as the invention becomes better understood by reference to the following description when considered in connection

with the accompanying drawings, in which—

Figures 1 and 2 are end views of a bolt of piece goods carrying label holders embodying my invention;

Fig. 3 is a top view of a combined label and sample holder removed from the bolt;

Fig. 4 is a rear view of said holder;

Fig. 5 is a perspective view of the wire frame of the holder;

Fig. 6 is a development of the sample pocket body before application to the label holder;

Fig. 7 is a perspective view of the label holder frame and sample pocket body assembled, and showing the sample holder in position;

Fig. 8 is a perspective view of the sample holder;

Fig. 9 is a view of a sample;

Fig. 10 is a detail view of the back of the label holder;

Fig. 11 is an enlarged vertical section through the center of the label holder shown in Fig. 1; and

Fig. 12 is a view of the label removed from the holder.

The means employed in practicing my novel method of merchandising piece goods may be of any suitable or preferred construction. In the present instance, I have for purpose of illustration shown a practical application of the method embodying a combined label and sample carrier of novel construction. The method will be explained after a description of the means utilized in its practice.

Referring now to Fig. 5, it will be observed that I have provided a wire frame adapted for carrying a label or tab in a display position at one end of a bolt of piece goods or the like. In the present instance, this frame is formed of a single piece of wire shaped medially to provide a label-holding portion 15, shoulders 16, and sides 17 terminating in ends 18 and 19, the former of which pass through a loop 21 formed by the latter. This construction permits the sides 17 to be separated or compressed laterally as may be desired in accommodating the holder to variations in the width of center-boards on which the piece material is wound. A suitable back 22 is applied to the label-holding portion 15, at present by

means of extensions 23 turned over the wire. A label 24 conforming in shape to the label holder proper, is adapted to be pressed into the circular portion 15 and to be retained 5 therein as shown in Fig. 11, by engagement of its peripheral edge between the back 22 and the holder portion 15. The back has an opening 25 permitting insertion of a hard object for ejecting the label. The 10 label-holding portion 15 will be shaped to accommodate labels of suitable or preferred shape and dimensions. For example, in Fig. 2 I have shown the portion 15' rectangular in shape to accommodate a similarly shaped label 24'.

In Fig. 6, I have shown the development of a sample body designed to be permanently attached to the label holder body. This body, preferably of a tough fibre paper 20 is shaped to provide a top portion 26 and a bottom portion 27, including end flaps 28 and 29 and side flaps 30 and 31. A retaining strip 33 will be glued onto one of the body portions at one side of their juncture as 25 shown in the drawing. Each portion of the body is cut away at said juncture as noted by numeral 34, to accommodate the looped end 21 of the wire frame when the latter is positioned in operative relation on 30 the body 26—27 as indicated in dotted lines, Fig. 6. This cutaway also facilitates flexing of the body portion after the parts are completely assembled, when the sides 17 are pressed inwardly, likewise compressing or 35 flexing said body. Before assembly of said body and the wire frame the ends 28 and 29 will be turned inwardly and glued to their respective body portions, thereby forming reinforced ends. The wire frame 40 will then be applied and the side flaps 31 will be turned inwardly over the sides 17 of the frame and glued to the body proper. The top portion 26 will then be folded over the ends 18—19 and glued along the strip 45 33 and the side flaps 30 will be turned over the longitudinal side edges of the body portion 27 and glued beneath the latter, as shown in Fig. 4. By reason of the foregoing construction the wire frame will be 50 securely locked in the paper body and the latter will form a pocket as clearly shown in Fig. 7, for the reception of a sample holder 35. It will also be observed that the pocket body is effectually reinforced at its 55 edges and firmly associated and secured in connection with the frame. This gives a very durable construction at a low cost. The sample holder 35 may be of any suitable or preferred construction, and at 60 present is shown in the form of connected covers adapted to open as a book for the reception of a plurality of samples 36. A piece of coarse pile velvet 37 is applied to the sample pocket body for retaining the 65 body in operative position by reason of the

engagement of such velvet pile with the goods.

The sample pocket body is also utilized for carrying an original entry record sheet for the reception of data with reference to 70 the particular piece goods with which the holder is associated. As shown in Fig. 3, I have printed on the top portion 26 certain titles for original entry of information for record and reference purposes. 75

Coming now to the method of merchandising referred to above, it will be noted that both the label 24 and the sample 36 carries data including a given number identifying the particular piece of goods, the price, the width of goods and the name by which it is known. The label on the sample also has the name of the seller, that is, the retailer. These samples are made from a strip cut from one end of the goods. It will thus be manifest that a single strip will furnish many samples, which will be individually labeled to correspond with the label 24 identifying the particular piece of goods. By this practice alone, a considerable saving in material is effected as it overcomes the custom of promiscuously cutting samples from the end of the material. The labeled samples are then placed in the holder 35 and the latter will be inserted in the 90 pocket. The label holder bearing the label 24 will then be inserted into the end of a bolt of piece goods, as shown in Fig. 1, in which the pocket portion and the sample carrier are completely concealed and the label holding end is positioned in the end of the center-board. In this position the shoulders 16 engage the ends of the material and assist in properly locating and holding the label holder in position. When now a 105 prospective purchaser desires a sample of any particular piece of material, it may be very quickly and conveniently furnished, simply by withdrawing the label-sample carrying body sufficiently to permit removal 110 of samples from the pocket therein. Should the recipient of the sample later desire to purchase, it will only be necessary to give the piece number, which immediately 115 and unquestionably identifies the particular material, thus avoiding mistakes and greatly simplifying merchandising of this kind of goods. The information contained on the sample pocket body remains identified with the particular piece of goods, and in the event it is desired to obtain further data with reference to the original cost, or any information not contained on the sample carrier, the book and page number given on said label enables quick reference to the 120 original invoice or to the proprietor's confidential records. It will be observed that the data contained on the sample carrier body is impersonal to the clerk, and that the proprietor of one in authority, may 125 130

quickly ascertain by referring back to the book records any confidential information respecting any particular piece of goods.

The printed titles on the sample-carrying body may be applied by means of a label or may be directly printed on the body according to individual desires. It will be noted that when the label 24 is in display position, it does not obstruct the trade mark or

10 trade name on the end of the center board.

By means of the method herein disclosed, the merchandising of piece goods is materially simplified and generally improved. It facilitates the keeping of records in connection with the goods, promotes convenience in selling, avoids confusion and mistakes in identifying the different goods and effects a saving both of material and time.

It is believed that the foregoing conveys a clear understanding of the objects prefaced above, and while I have illustrated but a single working embodiment, it should be understood that considerable change might be made in the form of the means for putting my improved method into practice, without departing from the spirit and scope of the invention as expressed in the appended claims.

I claim:

30 1. A label holder comprising a wire frame shaped to provide a label-carrying portion and longitudinal sides, the former of which is adapted to peripherally engage a label, and the latter to be inserted in the end of a bolt of piece goods for supporting said label-carrying portion in a display position, and a sample pocket body consisting of a top and a bottom portion having marginal edges folded over said sides for securing the body portion and said frame together, said body providing a pocket for the reception of samples.

40 2. A label and sample carrier to be used in the merchandising of piece goods comprising a label holder having a label-hold-

ing portion adapted to be supported in a display position at one end of a bolt of piece goods and a supporting portion adapted to be inserted into the end of said bolt in a concealed position and with said label-holding portion in a display position, a label on the face of said label-holding portion containing reference data including identification of the particular piece goods on the bolt, a sample holder separate from the label holder, and sample labels adapted to be attached to samples of the piece goods and having reference data including identification of the particular piece goods on said bolt, said sample holder being 55 constructed for carrying a plurality of said labeled samples, and said supporting portion of the label holder being constructed for carrying said sample holder and for permitting insertion of said sample holder 60 and removal thereof from said supporting portion without removing the label holder from its position on the bolt.

3. A label and sample carrier as set forth in claim 2, in which the supporting portion of the label holder has a forwardly and upwardly opening pocket for the reception of the sample holder.

4. A label carrier of the character described comprising a label holder having a label-holding portion and a supporting portion, the latter of which is adapted to be inserted into one end of a bolt of piece goods for supporting the label-holding portion in a display position, said label-holding portion being formed of a piece of wire bent to provide a marginal label engaging edge, and a back secured to said marginal wire portion and permitting insertion of the marginal edge of a label between said back and the wire so as to retain the label in position, said back having an opening for ejecting the label.

EDWARD SEYFARTH.
